UNITED STATES PATENT OFFICE.

SAMUEL MOREELL, OF CHICAGO, ILLINOIS.

BASCULE BRIDGE.

1,311,284.

Specification of Letters Patent. Patented July 29, 1919.

Application filed December 3, 1917, Serial No. 205,202. Renewed June 13, 1919. Serial No. 304,063.

To all whom it may concern:

Be it known that I, SAMUEL MOREELL, a citizen of the United States, residing at Chicago, in the county of Cook and State of Illinois, have invented new and useful Improvements in Bascule-Bridges, of which the following is a full, clear, concise, and exact description, reference being had to the accompanying drawing, forming a part of this specification.

My invention relates to improvements in bascule bridges of the type in which counterweights are provided for balancing the weight of the bridge spans.

One of the main objects of my invention is the provision of means for supporting the inner ends of bridge trunnions of such design and construction as to permit counterweights carried at the rear of the bridge spans to swing into a space directly below said trunnions during the operation of opening the bridge.

A further object is the provision of trunnion supporting means, the base of which is substantially vertically under the inner ends of the trunnions to be supported, utilizing a truss structure.

A further object is the provision of means whereby the point of application of the ultimate load may be shifted or made to occupy different positions with respect to the vertical line passing through the trunnion and liability of excessive lifting strain on the supporting masonry avoided.

A further object is the utilization of a bracing system for preventing vibration during movement and for taking wind stresses in both frame and moving leaf.

These and such other objects as may hereinafter appear are attained in my device, embodiments of which are illustrated in the accompanying drawings, in which—

Figure 1 represents a longitudinal section taken through the bridge on line 1—1 of Fig. 2, showing the relative positions of the counterweights and columns when the bridge is opened and indicating by dotted lines the closed position of the bridge.

Fig. 2 is a vertical transverse section of the bridge taken on line 2—2 of Fig. 1.

Fig. 3 is a detail plan section taken on line 3—3 of Fig. 1, showing clearance means employed in a counterweight.

Fig. 4 is a side elevation showing a modified form of truss-work for the trunnion support.

The form of construction as illustrated in the drawings comprises bridge trusses 1 of conventional design and provided with trunnions 2 which project inwardly and outwardly from the planes of the trusses as shown in Fig. 2. The trunnions 2 are arranged in axial alignment and the outer ends thereof, which are outside of the line of the bridge structure, are supported by columns 3 partially embedded in masonry forming the side walls of the pit. This masonry is preferably of concrete but other suitable materials may be employed such as granite, brick, etc. A roadway 6 is supported by means of cross girders 7 which extend from one truss to the other, this construction being clear by reference to Fig. 1. The usual rack and pinion employed for operating bridges of this character are omitted in the drawings for the sake of clearness of illustration.

The bridge counterweight 8 shown as a block of reinforced concrete is arranged at the rear of trusses 1, and extends from one truss to the other, there being cross girders 9 carried by said trusses which closely embrace and support said counterweight. Shouldered projections 10 extend from the rear ends of trusses 1 for engaging a girder 10 for supporting the bridge in the normal closed position thereof, said girder being suitably anchored by connection with the rear pit wall 11, as shown in Fig. 1. From Fig. 3 it will be seen that the path of movement of the ends of counterweight 8 extends to and beyond a perpendicular dropped from the inner end of trunnions 2, consequently suitable clearance must be provided in the inside trunnion supporting columns 12. This clearance is obtained by providing an offset for said column, as shown in Fig. 1. The offset portion is rigidly trussed in order that the strength of each column shall not be impaired. The truss-work comprises a forwardly extending member 13, which just clears the counterweight, a downwardly extending member 14, and a rearwardly extending member 15 which is riveted to the base of the member 14. Said members 13, 14 and 15 are rigidly braced by means of members 16, 17 and 18, which form a rigid construction.

The columns 12 above the truss-work therein are reinforced against lateral stresses by means of struts 19 which extend to the pit front wall 20, as shown in Figs. 2 and 3.

and against longitudinal pressure by the brace 5. Side struts 21 are also provided to reinforce the outside columns 3 against wind stresses, as shown in Fig. 2. The upper ends 5 of inside trunnion supporting columns 12 are connected by means of a horizontally extending laced member 22 which is thoroughly gusseted at the ends thereof with said columns for forming a substantial reinforcement. The member 22 in single decked bridges forms a support for the fixed portion of the roadway 6^a. In double decked bridges this will act simply as a lateral strut for the inside frame.

15 From Fig. 2 it will be observed that the bases of columns 3 and 12 are supported by sub-piers 23, but it is understood that any suitable foundation may be provided for this purpose. It will be seen that in order to 20 provide clearance for the braces 16 notches 24 are formed in the counterweight 8 as shown in Fig. 3.

The modified form of truss-work for reinforcing columns 12 shown in Fig. 4 comprises members 13, 14 and 15 as in the preferred form, but the braces are somewhat changed in arrangement. Other forms of trusses may be employed, and even a solid webbed construction would serve the purpose. This form is different from the preferred form in that the column base is offset slightly from a perpendicular dropped from the center of trunnion. The advantage resulting from this change is that the secondary stresses are such as to relieve vertical pressure on front wall 20, since vertical deformation of the column might cause an undesirable vertical load on the front wall 20.

40 By the use of my improved invention, the problem of vibration during motion and the wind stresses are taken care of. It is also possible in light bridges to use a plate girder construction for an inside support and an 45 economic design of moving truss is possible in using my frame.

I can use my invention with any type of foundation, sub-pier, pile or cross girder in the floor of the pit. I may also have the 50 frame come into the truss laterally, eliminating the cross girder but using a cantilever support.

By the use of my frame the reaction of the river pier can be regulated to any desired extent by changing the position of the other bearing point, that is with respect to the position of the vertical through the trunnion as shown in Fig. 4. The point of support being moved forward of the vertical through the trunnion depending upon the 60 desired downward load at the river pier.

It is evident then that I have provided for the support of an overhanging load upon a truss structure in such a manner as to produce no uplift upon the masonry supporting 65 said truss structure and that in order to attain this end it is simply necessary to properly locate the bearing points of the truss structure relative to the vertical line through the load acting upon the same.

70 It is evident that the truss construction shown in Fig. 4 may be inserted laterally at any desired angle and present a support for both bearings of any given trunnion.

75 While I have illustrated and described the preferred forms of construction for carrying my invention into effect, there might be variations and modifications without departing from the spirit of the invention. I, therefore, do not wish to be limited to the 80 precise details of construction set forth but desire to avail myself of such variations and modifications as come within the scope of the appended claims.

Having thus described my invention, what 85 I claim as new and desire to secure by Letters Patent is:

1. A bascule bridge comprising movable trusses, a counterweight therefor, trunnions on which the structure turns, inside column 90 supports for said trunnions, and supporting truss construction for said inside columns having an opening within which said counterweight may pass when it swings below said trunnions.

95 2. In a bascule bridge provided with movable trusses, a counterweight, the combination of trunnions for said trusses, a cantilever structure supporting said trunnions, said structure being cantilevered to permit the free swing of the counterweight when the bridge is in open position.

100 3. In a bascule bridge provided with movable trusses, a counterweight, the combination of the trunnions for said trusses, a construction supporting the ends of said trunnions, said construction having a cantilevered base and a cantilevered top, said construction being recessed to permit the free swing of the counterweight in the open position of the bridge.

105 In witness whereof I have hereunto subscribed my name.

SAMUEL MORELLI.
